UNITED STATES PATENT OFFICE.

ELBERT FOWLER, OF THE UNITED STATES ARMY.

MACHINE-GUN CASING.

Application filed December 4, 1918. Serial No. 265,240.

To all whom it may concern:

Be it known that I, ELBERT FOWLER, captain, Ordnance Department, United States Army, a citizen of the United States, stationed at Washington, District of Columbia, have invented an Improvement in Machine-Gun Casings, of which the following is a specification.

The object of my invention is to provide 10 a machine gun in which the breech casing and water jacket are axially aligned and in one integral piece.

As machine guns have heretofore been constructed, the breech casing and the water 15 jacket have been two separate members suitably connected as by a screw threaded connection (as in the well known Browning gun), and the water jacket has been offset with relation to the breech casing, so 20 that the barrel of the gun lies below the longitudinal center of the water jacket and adjacent the bottom thereof, for a purpose well known to those acquainted with machine guns, namely, to keep the barrel 25 covered with a cooling medium when the gun is tilted. Experience has shown that a machine gun comprising a water jacket and a breech casing united by a threaded joint presents disadvantages, because the gun 30 sometimes breaks at the joint and, even if no break occurs, the shock and vibration of the gun in use tend to strip the threads, causing leakage at the joint.

Another object is to provide a novel arrangement of the barrel with relation to the water jacket, whereby, notwithstanding the fact that the breech casing and cooling jacket are in axial alinement, and not offset, as in other constructions, no portion 40 of the barrel exposed to the cooling medium when the gun is in a horizontal plane will be exposed by said medium when the gun is tilted, so as to incline upward.

Another object is to provide novel means 45 for securing and locking the rear end plate of the gun.

Another object is to provide a locking means, common to both the end plate and cover of the gun, for locking both or for 50 selectively unlocking either.

Another object is to provide a novel means for permitting inlet of water to the water jacket.

Another object is to provide a novel construction of support for the bearing of the 55

pivot or trunnion upon which the machine gun is pivotally supported upon a tripod.

Other objects will appear as the invention is disclosed.

The invention is illustrated in the accompanying drawings, which disclose one embodiment thereof.

Fig. 1 is a view in side elevation of a machine gun constructed in accordance with my invention.

Fig. 2 is a central longitudinal sectional view thereof.

Fig. 3 is a detached detail view, in rear elevation, of the rear end plate or handle-block.

Figs. 4 and 5 are sectional views on the lines 4-4 and 5-5 respectively, Fig. 1.

Referring now in detail to the drawing:

As shown, the water-jacket 1 and the breech casing 2 are integral and coaxial, 70 and are formed of a single piece of tubing.

The water jacket 1 at its forward end is internally threaded, as shown at 3, for engagement with the threaded end of the cap 4 provided with a tubular, re-entrant bearing 5, through which slides the barrel 6, the bushing 7 being screwed into the end of the bearing 5 around the barrel 6, to provide a water tight joint.

The water jacket, towards its rear end, is 85 provided with a thickened portion 8, provided with screw threads 9, for engagement with the exterior screw threads of the member 10. The barrel 6 is slidably mounted in the tubular, upwardly and rearwardly 90 inclined bearing 11, which forms a part of the member 10.

It will be noted in the construction described, that the barrel 6 is disposed in a position which is inclined to the axis of the 95 water jacket 1, the barrel inclining forwardly toward the bottom of the water jacket, so that, when the barrel is tilted upward, the water level is still over the barrel.

The water jacket 1 is provided with a threaded circular aperture 12 in which is threaded a cup-shaped valve-casing 13, having an annular flange 14 for engaging the outer surface of the water jacket, and an 105 internal valve seat 15, against which is normally seated a disk-valve 16, having a stem 17 slidable in a bearing 18 in the bottom of the cup-shaped casing 13.

Between the valve 16 and the bottom of 110

the casing is disposed a coiled spring 19, tending to maintain the valve 16 against its seat. The valve-casing 13 is provided with one or more apertures 20 in its vertical wall, for the passage of water when the valve 16 is opened. The rear end plate or handle block 21 is bowed, as shown, for the purpose of increased strength, and is provided with a flange 22, having exterior parallel ribs extending partially around the circumference thereof and engageable with corresponding grooves in the rear end of the breech casing 2. As shown, in this instance, there are two diametrically-oppositely disposed pairs of ribs on the flange 22 and two diametrically opposite pairs of grooves in the breech casing 2. The handle block or plate 21 is assembled with the breech casing by sliding it into the end of the latter until one end of the ribs registers with the corresponding end of the grooves; then by a partial turn of the handle block the ribs enter the grooves, so that the handle-block is held against longitudinal removal.

25 To secure the handle-block against accidental withdrawal by rotation thereof, due to shock and vibration, suitable mechanism may be provided. In this instance, I have shown the end plate 21 as provided with two lugs 23, between which is adapted to protect a slideable latch 24, provided with an operating-stem 25, projecting through a longitudinally extending slot 26, in the breech casing 2, and provided, at its exterior end, with a handle 27.

As shown in Figure 2, the latch is common to both the handle block 21 and the hinged cover 28 of the breech casing, and is operable to lock both or selectively to 40 unlock either the cover 28 or the cover and handle blocks 21.

The forward end of the slideable latch is engageable with a recess in the lug 29 carried by the cover 28 on the end surface 45 thereof.

Referring especially to Fig. 2 of the drawing, it is evident that there is sufficient clearance between the rear end of the latch bar 24 and the flange 22 to permit the latch bar to be slid rearwardly a sufficient distance to disengage the forward end from the recess in the lug 29 of the cover plate 28. When the latch bar is so moved rearwardly the cover plate is unlatched and may 55 be swung upwardly so that the latch bar may then be forced forwardly to disengage the rear end from between the lugs 23, which will free the handle block and allow the same to be rotated and removed.

60 Carried by the rear end of the water jacket is a split cover or ring 30 having internal, circumferential, marginal flanges 31. The ring is provided adjacent the split 32 with apertured ears 33, 33. Through the apertures of the ears 33, 33 passes a tubular

bearing 34. In assembling the ring 30 and the tubular member 34, in manufacturing the gun, the ring 30 is slipped onto the water jacket 1 and moved to the position thereof shown in Figs. 1 and 2. The ears 33 are then placed in a vise, and the vise jaws closed to move the ears toward each other, thus contracting the ring or collar 30 tightly around the water jacket 1. The tubular member 34, previously heated to a malleable condition, is then slipped through the apertures in the ears 33, 33 while hot. The tubular member 34 is provided with a circumferential flange or upset end 35, the other projecting end of the tube 34 being plain. A swaging tool is then used to upset said other projecting end of the tube against the ear 33, as shown in Fig. 5, at 36. This swaging or upsetting is done while the metallic tube 34 is still hot and malleable. As the tube 34 cools, it contracts, binding the collar 30 more tightly against the water jacket 1. The collar 30 is thus, as it were, shrunk upon the water jacket 1.

From the above detailed description and arrangement of the different parts, the many advantages of my invention will be apparent, especially to those skilled in the art to which the invention pertains. Among such advantages may be mentioned the following:

1. From the construction of the water jacket and breech casing in one piece the following beneficial results are obtained:

(a) A considerable saving in time in the manufacture of the gun, (b) the water jacket and the breech casing are stronger than when made in two pieces (as above pointed out), (c) there is no danger of leakage of the water because there is no joint between the water jacket and the breech casing.

2. The arrangement of the barrel at an incline with respect to the axis of the water jacket permits a coaxial relationship of the water jacket and the breech casing, and avoids the necessity of offsetting the water jacket with relation to the breech casing, that is, of disposing the water jacket and the breech casing in non-concentric relationship. The barrel being inclined with respect to the water chamber permits the gun to be tilted upward, thus maintaining the level of the water above the barrel at all points thereof within the water jacket.

3. The provision of the locking latch common to both the breech cover and the handle block obviates the expense of separate latches for these parts, and the additional labor of assembling two parts.

4. The construction of the collar 30 and the method of assembling therewith the tubular bearing 34 insure a firm and immovable seating of said bushing on the water jacket.

Having thus fully described my invention what I claim as new and desire to secure by Letters Patent is—

1. In a machine gun, the combination, 5 with a breech casing having a movable cover, of a rear end plate rotatably engageable with said breech casing, and means common to both said cover and said plate for locking the cover and for also locking the plate 10 against accidental rotation.
2. In a machine gun, the combination,

with a breech casing having a movable cover, of a rear end plate rotatable engageable with said breech casing, and a slid able latch common to both said cover and said 15 plate for locking the cover and for also locking the plate against accidental rotation.

In testimony whereof I affix my signature.

ELBERT FOWLER.
